DESIGN FOR A LIGHTING FIXTURE

Chauncey E. Waltman, Chicago, Ill., assignor to Benjamin Electric Mfg. Company, Des Plaines,
Ill., a corporation of Illinois

Application March 6, 1939, Serial No. 83,360

Term of patent 7 years

To all whom it may concern:

Be it known that I, Chauncey E. Waltman, a citizen of the United States, residing at Chicago, in the county of Cook and State of Illinois, have invented a new, original, and ornamental Design for a Lighting Fixture, of which the following is a specification, reference being had to the accompanying drawing, forming a part thereof.

In the drawing,

Fig. 1 is a side elevational view of a lighting fixture embodying my new design;

Fig. 2 is an end view thereof; and

Fig. 3 is a perspective view from one side looking upwardly at the fixture.

I claim:

The ornamental design for a lighting fixture, substantially as shown.

CHAUNCEY E. WALTMAN.
